US00D942456S

(12) **United States Design Patent** (10) **Patent No.:** **US D942,456 S**
Liao (45) **Date of Patent:** **** Feb. 1, 2022**

(54) **PORTABLE ELECTRONIC DEVICE CASE**

(71) Applicant: **Shenzhen Lanbo Technology Co., Ltd.**, Guangdong (CN)

(72) Inventor: **Runzhen Liao**, Guangdong (CN)

(73) Assignee: **SHENZHEN LANBO TECHNOLOGY CO., LTD.**, Guangdong (CN)

(**) Term: **15 Years**

(21) Appl. No.: **29/730,780**

(22) Filed: **Apr. 8, 2020**

(30) **Foreign Application Priority Data**

Dec. 30, 2019 (CN) 201930741412.4

(51) **LOC (13) Cl.** **14-02**

(52) **U.S. Cl.**

USPC **D14/440**

(58) **Field of Classification Search**

(57) **CLAIM**

The ornamental design for a portable electronic device case, as shown and described.

DESCRIPTION

FIG. 1 is a front elevational view of a first embodiment of a portable electronic device case showing my new design; FIG. 2 is a rear elevational view thereof; FIG. 3 is a left side view thereof; FIG. 4 is a right side view thereof; FIG. 5 is a top plan view thereof; FIG. 6 is a bottom plan view thereof; FIG. 7 is a front perspective view thereof; FIG. 8 is a rear perspective view thereof; FIG. 9 is a first perspective view of the first embodiment of the portable electronic device case in use; FIG. 10 is a second perspective view of the first embodiment of the portable electronic device case in use; FIG. 11 is a front elevational view of a second embodiment of a portable electronic device case showing my new design; FIG. 12 is a rear elevational view thereof; FIG. 13 is a left side view thereof; FIG. 14 is a right side view thereof; FIG. 15 is a top plan view thereof; FIG. 16 is a bottom plan view thereof; FIG. 17 is a front perspective view thereof; FIG. 18 is a rear perspective view thereof; FIG. 19 is a first perspective view of the second embodiment of the portable electronic device case in use; and, FIG. 20 is a second perspective view of the second embodiment of the portable electronic device case in use.
